UNITED STATES PATENT OFFICE.

FRED W. LORD, OF TIPTON, INDIANA, ASSIGNOR TO THE OAKES MANUFACTURING COMPANY, OF TIPTON, INDIANA.

FURNACE BROODER.

Application filed March 12, 1927. Serial No. 174,813.

My said invention relates to brooders and it is an object of the invention to provide a thermostatically controlled coal burning brooder stove or heater and a sectional heat deflecting or retaining canopy capable of being telescoped or collapsed to permit access to the brooder stove.

Referring to the accompanying drawings which are made a part hereof and on which 10 similar reference characters indicate similar parts,

Figure 1 is a perspective of a brooder constructed in accordance with my invention with the sections of the heat retaining canopy collapsed,

Figure 2, a fragmentary vertical section with the parts of the heat retaining canopy in the same position as shown in Figure 1,

Figure 3, a top plan view with the sections 20 of the canopy in wide spread operative position,

Figure 4, a vertical section through a stove showing means for adapting the stove to burn hard coal, and

Figure 5, a detail perspective of the connecting link and draft door lever.

In the drawings reference character 10 indicates a brooder stove, 11 the ash pit and 12 a draft door. The stove 10 preferably comprises a sheet iron body provided with a cast iron top 13 having the usual lid and smoke outlet. The top 13 is provided with a circular depending flange 14 adapted to fit into the upper end of the sheet iron jacket 30 to which it may be secured by any desired fastening means. The top is also provided with an outwardly and downwardly tapering portion which terminates in an external flange or shelf 15 arranged to support a canopy or heat retaining shell 16. The canopy or heat retaining shell 16 comprises a pair of rings or collars 17 and 18 to each of which is connected, by any suitable fastening means, such as rivets or the like, oppositely disposed

45 quarter sections or segments of the canopy. The lower ring 17 rests directly on the flange or shelf 15 of the stove top while the ring 18 is supported directly on the ring 17. Each section of the canopy forms a heat reflector

50 and when the sections are disposed in non-collapsed relation, as shown in Fig. 3, a complete body of heated air is constantly maintained beneath the same. Each of the four canopy sections 16 is rolled over at its lower 55 edge in order to strengthen the same and in

order that these rolled over edges may not interfere, I provide the upper sections with upwardly extending rolled over portions 19 and the lower sections with depending rolled over portions 20 and I also bend the lower 60 corners of each of the lower sections downwardly at 21 to keep them from interfering with the upper sections when the parts are being moved to the collapsed or telescoped position.

65 It will be obvious that with this construction it is possible to revolve both pairs of quarter sections of the canopy by revolving one pair. Also since these sections are held on only by gravity they may be readily removed since the ring or collar to which one set is attached supports the other set to permit fuel to be supplied to the furnace, ashes to be removed for cleaning or any other purpose for which it is desirable to have greater 70 access to the stove than is possible from the outer edge of the canopy.

75 The ash pit or draft door 12 is provided with an operating rod 12' which extends from one end of the same outwardly and downwardly to form an operating member for the door. Towards the rear of the furnace is mounted a bracket 22 which supports at its outer end a thermostat 23 which is adapted to operate an arm 24 and a lever 25 for reciprocating an adjustable link 26 for opening and closing the draft door 12. The end of the rod or link 26 which engages the draft door operating rod is bent rearwardly upon itself and then curved around to 90 form a bifurcated end 27 (Fig. 5) in which is disposed the operating rod 12' which is connected to the draft door.

95 The thermostat and associated parts are disposed at a sufficient height so that they do not interfere with and are not interfered with by the chicks and said thermostat will function in the well known manner of maintaining heat at a uniform temperature.

100 In Figure 4 of the drawings is illustrated the furnace provided with an attachment for burning hard coal. A centrally disposed chamber 30 having an outwardly extending flange 31 at its upper end is adapted to fit into the lid opening in the top 13 and has its 105 lower end terminating above the center of the grate to form a chute or feed chamber for the unburnt coal.

110 It will be obvious to those skilled in the art that various changes may be made in

my device without departing from the spirit of my invention, and I, therefore, do not limit myself to what is shown in the drawings and described in the specification, but 5 only as set forth in the appended claims.

Having thus fully described my said invention, what I claim as new and desire to secure by Letters Patent, is:

1. A brooder comprising a central up-
10 standing supporting element, an overhang-
ing depending annular canopy supported
from the upper end of said supporting ele-
ment said canopy comprising a plurality of
15 slidably mounted sections slidable one over
the other to afford access to the supporting
element, substantially as set forth.

2. A brooder comprising a central up-
standing supporting element, a pair of rings
resting on the upper end of said supporting
20 element, and similar spaced canopy segments
on each of said rings, said rings being slid-
able relatively one to the other to permit the
canopy segments on one ring to close the
25 openings between the canopy segments on
the other ring, substantially as set forth.

3. A brooder comprising a central up-
standing supporting element having a mar-
ginal flange about its upper end, a ring rest-
ing upon said flange and provided with
20 spaced arcuate canopy sections, a second
ring resting on the first-mentioned ring,
canopy sections mounted on said second ring
in spaced relation corresponding to the
spacing of the first segments whereby the
25 rings may be rotated relative to each other
to arrange the sections in continuous rela-
tion to form an annular canopy or said sec-
tions can be disposed over each other to af-
ford access between the canopy sections, sub-
30 stantially as set forth.

4. A brooder comprising a stove and a
pair of rings supported at the upper end
of the stove, each of said rings having dia-
metrically opposed sections each equivalent
45 to one-fourth of the curved surfaces of a
frustum of a cone, one of said rings being
adapted to be rotated to arrange the canopy

sections supported thereby either in stag-
gered relation to provide an annular canopy
or over the canopy sections of the other 50
ring to afford access to the stove, substan-
tially as set forth.

5. A brooder comprising a stove and a
pair of members supported at the upper end
of the stove, each of said members having
diametrically opposed sections, one of said
members being adapted to be rotated to ar-
range the canopy sections supported thereby
either in staggered relation to provide an
annular canopy or over the canopy sections 60
of the other member to afford access to the
stove, and a thermostat disposed beneath
said canopy for controlling the operation of
said stove, substantially as set forth.

6. A brooder comprising a heat retaining
canopy formed of slidable sections disposed
in staggered relation and a coal burning
brooder stove comprising an ash pit, a com-
bustion chamber, a top and a detachable cen-
tral tube supported by said top for adapt-
ing said stove to burn hard coal, substan-
tially as set forth.

7. A brooder comprising a heat retaining
canopy formed of slidable sections disposed
in staggered relation and a coal burning
brooder stove comprising an ash pit, a com-
bustion chamber, a top, a lid opening in said
top and a detachable central tube having an
outwardly extending flange at its upper end
adapted to fit said lid opening to form a 80
chute or feed chamber for unburnt coal,
substantially as set forth.

8. A brooder comprising a supporting ele-
ment, a canopy supported by said support-
ing element and comprising groups of 85
spaced segments, the segments constituting
one group being slidable relative to the seg-
ments of another group and to said support-
ing element, substantially as set forth.

In witness whereof, I have hereunto set 90
my hand at Tipton, Indiana, this 10th day
of March, A. D. nineteen hundred and
twenty-seven.

FRED W. LORD.
